UNITED STATES PATENT OFFICE.

MAX JERSEMAN, OF NEW YORK, N. Y.

SUSPENSION DEVICE FOR WATCHES AND OTHER ARTICLES.

Application filed July 24, 1923. Serial No. 653,443.

To all whom it may concern:

Be it known that I, MAX JERSEMAN, a citizen of the United States, residing at New York, in the county of New York and State 5 of New York, have invented certain new and useful Improvements in Suspension Devices for Watches and Other Articles, of which the following is a specification.

My invention relates to means for suspending 10 watches or other articles, and more particularly consists in a resilient hook, which is so designed and constructed that irrespective of the position of the device, the watch or other article cannot become dislodged, but is securely held in position.

In the accompanying drawing in which I have illustrated my invention by way of example, Fig. 1 is an end view of the new device fastened to a board. Fig. 2 is a front 20 elevation. Fig. 3 a section along line 3—3 in Fig. 2, and Fig. 4 a perspective view of the device.

The device is preferably made of spring metal and is made in one piece, the parts 25 being stamped out of the metal and then being bent into position.

As shown in Fig. 4, the device consists of the body portion 1, from which is stamped out a tongue 2, which is then bent forwards 30 and downwards, and backwards, as clearly shown in Figs. 1, 3 and 4. With this tongue 2, cooperates a longer tongue 3, which projects from the body portion 1, and is bent upwards, forming a curved resilient hook, 35 from which may be suspended a watch, as shown at 4 in Fig. 1 by the broken lines, or any other article. As will be evident from Fig. 1, after the ring 5 of the watch has been slipped over the hook 3, the watch 40 cannot become dislodged, no matter in what position the device for suspending the watch is held. In order to remove the watch from the hook 3, some force is required to separate the slightly curved end of the hook 3 45 from the bent-over tongue 2, so as to permit the watch to be released. At opposite ends of the body portion 1, upturned small hooks 6 and 7 are formed, whereby a small card,

such as shown at 8 in Figs. 1 and 2, is firmly held in position. This card 8 is intended 50 to have the price of the watch or other article noted thereon, or to receive other marks having reference to the suspended article.

As seen in Fig. 4, two holes 9, 10 are provided in the body portion 1, adapted to receive small screws shown at 11 in Fig. 1, whereby the device may be fastened to a board 12, or the like.

The device can be very cheaply and easily 60 manufactured, and it is to be understood that I do not wish to limit myself to the device as actually shown on the drawing, as the parts can be modified without departing from the principle of the invention.

What I claim is:

1. A suspension device for watches and other articles, comprising a plate of spring metal, a tongue stamped out of said metal and bent downwards to form an abutment, 70 a second tongue integral with the plate and curved upwards forming a hook cooperating with said abutment, the said plate being formed at its lower edge with two small lugs slightly curved inwardly and bent so 75 as to be parallel with the plane of the said plate, and adapted to firmly grip and hold a card.

2. A suspension device for watches and other articles, comprising a plate of spring 80 metal, a tongue stamped from the said metal and bent away from said plate substantially at right angles and then backwards, so as to form an abutment, a second tongue formed integral with the said plate in the 85 same plane therewith and bent upwardly, forming a hook lying close to said abutment, the latter closing the mouth of the hook, and two slightly inwardly curved lugs formed from the metal of the said plate 90 and bent parallel to said plate to form clamps therewith, the said plate being provided with holes for the insertion of screws to fasten the said plate to a board.

In testimony whereof I affix my signature.
MAX JERSEMAN.
